ABSTRACT OF THE DISCLOSURE

Oxidation dye coupling compounds for use in dyeing live human hair having the formula:

SUMMARY OF THE INVENTION

There are methods of dyeing keratinic fibers, and particularly human hair, in which the hair is dyed by means of compositions containing oxidation dyes, and in particular by means of aromatic ortho or para-diamines and ortho- or para-aminophenols, which are generally referred to as "oxidation bases." It is also conventional to vary the shades obtained with these bases by utilizing color modifiers or "couplers" and, in particular, aromatic meta diamines and meta aminophenols.

The present invention relates to a new class of couplers which may be used with known oxidation dyes. It is the object of the invention to provide as a new article of manufacture a dye for keratinic fibers, and particularly for human hair, which is essentially characterized by the fact that it contains, in association with at least one conventional oxidation base, at least one benzomorpholine compound having the general formula:

in which X represents sulfur or oxygen, R represents hydroxyl or amino in position 5 or 7, R₁ and R₂ represent hydrogen, lower alkyl having 1-4 carbon atoms or lower hydroxyl alkyl having 1-4 carbon atoms, and R₃ is H or lower alkyl having 1 to 4 carbon atoms. These compounds may be used in the form of their mineral or organic acid addition salts. Among the bases which may be advantageously used in association with the couplers of Formula I are: para-phenylene diamine, para-tolylene diamine, para-aminophenol, N-methyl-para-aminophenol, chloro-para-phenylene diamine, methoxy-para-phenylene diamine, 6-methoxy-3-methyl-para-phenylene diamine, (N-ethyl, N-carbamylethyl)para-phenylene-diamine, 2,5-diamino-pyridine.

Among the couplers having Formula I are: 7-hydroxy-

2

benzomorpholine, 7-amino-benzomorpholine, 5-hydroxy-benzomorpholine, 5-amino-benzomorpholine, 1-methyl-7-hydroxy-benzomorpholine, 2-methyl-7-hydroxy-benzomorpholine and 5-hydroxy-7-methyl-benzomorpholine.

5 The ratio of base to coupler in the dyeing compositions according to the invention may vary within broad limits, but an excess of coupler is preferably used.

The dyeing compositions of this invention may contain other dyes suitable for use under the same conditions, including direct dyes (such as azo or anthraquinone dyes), or dyes obtained by the association of bases and couplers other than those constituting the subject matter of the present invention.

The compositions of this invention may also contain 15 wetting agents, dispersing agents, penetrating agents, or any other ingredients conventionally used in dyeing hair. They may take the form of an aqueous solution, a cream, a gel or an aerosol.

The compositions according to the invention are used 20 in a conventional manner at an alkaline pH, preferably between 8 and 10. This pH may be obtained, for example, by adding ammonia or some other base. The composition is applied to the hair in the presence of an oxidizing solution, which is preferably a solution of hydrogen peroxide.

It is a further object of the present invention to provide a method of dyeing hair which is characterized by making the dye composition defined above alkaline, adding hydrogen peroxide thereto and applying the mixture to 30 the hair. The hair is then rinsed, shampooed and dried.

A further object of the invention is to provide new compounds having the Formula I in which R represents hydroxyl, that is to say those compounds having the formula:

35 in which the OH radical is in position 5 or 7. These compounds may be prepared from 2,3-dimethoxy or 2,5-dimethoxy aniline, by condensation with glycol bromohydrin followed by cyclization with hydrobromic acid.

40 45 This method has been described in the prior art literature for use in preparing benzomorpholine.

It is a further object of the present invention to provide 50 a new method of preparing compounds of Formula I in which R represents amino, that is to say those compounds having the formula:

55 in which the amino group is in position 5 or 7. In this process chloroethyl chloroformate is condensed in a first step with a 2-methoxy-5-nitro aniline or with a 2-methoxy-3-nitro aniline in order to obtain the corresponding chloroethyl carbamate. This is cyclized with a strong mineral base such as sodium hydroxide or potassium hydroxide. Then the nitro group of the resulting compound is reduced with a reducing agent, such as iron in an aqueous acetic acid medium.

The following examples illustrate the different forms of the invention. In these examples, which are purely illustrative, the percentages are given by weight and the temperatures are indicated in degrees Celsius, that is to say degrees centigrade.

EXAMPLES OF PREPARATION

Example 1.—Preparation of 7-hydroxy benzomorpholine

This process may be schematically described as follows: 10

(1) Preparation of 2,5-dimethoxy-N-(β-hydroxyethyl) aniline.—A mixture containing 100 g. (0.654 mole) of 2,5-dimethoxy aniline, 147.5 g. (0.825 mole) of 70% glycol bromohydrin, 45 g. (0.45 mole) of calcium carbonate and 500 cm.³ of water is heated at reflux for 4 hours. After cooling and filtering the reaction mixture, it is extracted using ethyl acetate. The solvent is eliminated under vacuum and the oily residue is fractionally distilled. The yield is 62 g. of 2,5-dimethoxy-N-(β-hydroxyethyl) aniline, boiling point at 0.05 m.=137–142°, melting point=48.5°, which analyzes as follows:

Analysis.—Calculated for C₁₀H₁₅NO₃ (percent): C, 60.91; H, 7.61; N, 7.10. Found (percent): C, 60.81; H, 7.63; N, 7.01.

(2) Preparation of 7 - hydroxy-benzomorpholine.—8 g. (0.04 mole) of 2,5 - dimethoxy-N-(β-hydroxyethyl) aniline are heated at reflux for 2 hours in 40 cm.³ of hydrobromic acid having a density of 1.78. After cooling the reaction mixture, 6 g. of 7-hydroxy-benzomorpholine hydrobromide are separated out by drying. This hydrobromide is dissolved in water and the aqueous solution is neutralized with ammonia. Drying then yields 3.5 g. of 7-hydroxy-benzomorpholine which, after recrystallization in toluene, melts at 115°.

Analysis.—Calculated for C₈H₉NO₂ (percent): C, 63.57; H, 5.96; N, 9.27. Found (percent): C, 63.51; H, 6.02; N, 9.44.

Example 2.—Preparation of 7-amino-benzomorpholine

This process may be schematically represented as follows:

(1) Preparation of β-chloroethyl-N-[(2 - methoxy-5-nitro) phenyl] carbamate.—63 g. (0.37 mole) of 2-amino-4-nitro anisole are dissolved in 190 cm.³ of dioxane. 26 g. (0.26 mole) of calcium carbonate are then added. The mixture is brought to reflux and 63 g. (0.44 mole) of β-chloroethyl chloroformate are added little by little. After heating for an hour the boiling liquid is filtered. The filtrate is cooled, and drying yields 90 g. of β-chloroethyl - N - [(2 - methoxy - 5 - nitro) phenyl] carbamate which, after recrystallization in dioxane, melts at 130°.

(2) Preparation of 7-nitro-benzomorpholine.—68.6 g. (0.25 mole) β - chloroethyl - N - [(2 - methoxy-5-nitro) phenyl] carbamate are added to 600 cm.³ of ethyl alcohol at 95° containing 66 g. of 85% potassium hydroxide. This is heated at reflux for 2 hours under a nitrogen atmosphere. After cooling, the reaction mixture is diluted with 2 liters of ice water and drying yields 43 g. of 7-nitro-benzomorpholine which, after recrystallization in benzene, melts at 120°.

Analysis.—Calculated for C₈H₈O₃N₂ (percent): C, 53.30; H, 4.44; N, 15.55. Found (percent): C, 53.51, 53.40; H, 4.48, 4.60; N, 15.49, 15.54.

(3) Preparation of 1 - acetyl - 7 - acetylamino-benzomorpholine.—7 g. (0.039 mole) of 7 - nitro-benzomorpholine are introduced into 40 cm.³ of water containing 1.5 cm.³ of acetic acid and 8.8 g. of iron powder. The reaction mixture is brought to 80° for 20 minutes and neutralized with sodium carbonate. It is boiled dry and the filtrate introduced directly into 15 cm.³ of acetic anhydride. After cooling, drying yields 6.5 g. of 1-acetyl-7 - acetylamino-benzomorpholine which, after recrystallization in alcohol, melts at 198°.

Analysis.—Calculated for C₁₂H₁₄N₂O₃ (percent): C, 61.53; H, 5.98; N, 11.96. Found (percent): C, 61.93, 61.91; H, 6.22, 6.22; N, 11.91, 11.92.

(4) Preparation of 7 - amino - benzomorpholine dihydrochloride.—3 g. (0.0138 mole) of 1-acetyl-7-acetyl-amino-benzomorpholine are introduced into 9 cm.³ of concentrated hydrochloric acid, and the reaction mixture is brought to reflux for 2 hours. After cooling to –10°, drying yields 2.3 g. of 7 - amino - benzomorpholine dihydrochloride which melts and decomposes at 235–240°. Calculated molecular weight for C₈H₁₂N₂OCl₂:223. Molecular weight found by potentiometric measurement:233.

EXAMPLES OF APPLICATION

Example 3

60 The following dyeing solution is prepared:

	G.
Para-toluylene diamine	1
7-amino-benzomorpholine dihydrochloride	0.8
65 20% ammonium lauryl sulfate, that is to say aqueous ammonium lauryl sulfate solution, the concentration of which is 20% as referred to lauryl alcohol	200
Ethylene diamino tetra acetic acid	3
70 20% ammonia	100
40% sodium bisulfite	10
Water q.s.p. 1000 g.	

This solution, when mixed with an equal weight of 6% hydrogen peroxide and applied for 30 minutes to 75 100% white hair, produces a purplish-blue.

2. The composition of claim 1 in which the base is selected from the group consisting of para-phenylene diamine, para - toluylene - diamine, para - aminophenol, N-methyl-para-aminophenol, 6 - methoxy-3-methyl-para-phenylene diamine, (N-ethyl, N-carbamyl-ethyl)-para-phenylene diamine and 2,5-diaminopyridine. 5

3. The composition of claim 1 in which the coupler is selected from the group consisting of 7-hydroxy-benzomorpholine, 5-hydroxy-benzomorpholine, 7-amino-benzo- 10 morpholine, 5-amino-benzomorpholine, 1 - methyl-7-hydroxy-benzomorpholine, 2-methyl 7 - hydroxy-benzomorpholine and 5-hydroxy 7-methyl-benzomorpholine.

4. A process for dyeing live human hair comprising 15 applying in amounts effective to dye said hair, the composition of claim 1.
